CAMPING TRAILER

David B. Smith, Worthington, and James P. Soroos, Columbus, Ohio, and Patrick J. Regan, Wichita, Kans., assignors to The Coleman Company, Inc., Wichita, Kans., a corporation of Kansas

Filed Oct. 26, 1967, Ser. No. 9,182

Term of patent 14 years

(Cl. D14—3)

FIG. 1

FIG. 2

FIG. 3

FIG. 4

FIG. 5

FIG. 6

FIG. 1 is a perspective view of a camping trailer embodying our new design;

FIG. 2 is an end elevational view from the right side of FIG. 1;

FIG. 3 is an end elevational view from the left side of FIG. 1;

FIG. 4 is a side elevational view of the side shown in FIG. 1;

FIG. 5 is a side elevational view of the opposite side; and

FIG. 6 is a top plan view with the side of FIG. 5 at the bottom.

The design of this invention is characterized by the arched configuration of the projecting end portions of the camping trailer, as shown more clearly in FIGS. 1, 2 and 3.

We claim:

The ornamental design for a camping trailer, as shown and described.
